N. I. FOSTER AND H. B. LUPIEN,
ATTACHMENT FOR LEATHER SKIVING MACHINES.
APPLICATION FILED JULY 19, 1920.

1,403,240.

Patented Jan. 10, 1922.

Inventors:

UNITED STATES PATENT OFFICE.

NELLIE I. FOSTER AND HENRY B. LUPIEN, OF MANCHESTER, NEW HAMPSHIRE.

ATTACHMENT FOR LEATHER-SKIVING MACHINES.

1,403,240.

Specification of Letters Patent. Patented Jan. 10, 1922.

Application filed July 19, 1920. Serial No. 397,347.

To all whom it may concern:

Be it known that we, NELLIE I. FOSTER and HENRY B. LUPIEN, citizens of the United States of America, and residents of the city 5 of Manchester, in the State of New Hampshire, have invented certain new and useful Improvements in Attachments for Leather-Skiving Machines, of which the following is a specification.

- 10 Our invention relates to leather skiving machines such as are in common use in the shoe industry for skiving "upper leather," whereby a skiving is removed in a continuous strip.
- 15 Briefly, the machine, which forms no part of our invention, comprises a feed roll, a presser foot for holding the leather to be skived against the feed roll, a rotary horizontal feed disk adapted to further support 20 the leather against the feed roll, and a rotary disk knife arranged at an angle and adapted to skive the leather so as to leave a bevel edge.

The skiving, when it reaches a considerable length, often winds around the shaft of the rapidly revolving disk knife and either clogs or otherwise damages the machine.

The object of our invention is to provide an attachment which may be readily installed upon the conventional skiving machines now in common use, whereby the skiving, at the moment after cutting, is deflected away from the moving parts of the machine, thereby preventing any delay in 35 operation or damage thereto.

Our invention is described in the following specification, and illustrated in the accompanying drawing, in which—

Figure 1 is a plan view of a portion of a 40 skiving machine equipped with our device; Fig. 2, is a side elevation of Fig. 1; and Fig. 3, is a detail of our invention.

The parts shown in the drawing are well known elements of an ordinary skiving machine and include a feed roll 1, having an enlarged roughened surface 2, a horizontal feed disk 3 arranged substantially perpendicularly to the feed roll and journaled in a bearing 4, a presser foot 5, and a rotary disk knife 6, which is journaled in a fixed bearing 7.

"A" designates a piece of leather stock from which a skiving "B" is being removed.

Our invention, which is shown in detail in 55 Fig. 3, consists of two main members, 8 and 9, each having a semi-circular portion 10,

said members being detachably secured or hinged at one side as by a hinge 11, and adapted to be detachably secured at the opposite side as by a screw 12 passing 60 through an aperture in an outturned end 13 of the member 8, and engaging a threaded recess in a relatively long outturned portion 14 of the member 9.

The member 8 has an integral wing 15 65 extending considerably beyond the semi-circular portion.

The relatively long outturned portion 14 of the member 9 has an aperture 17 therein through which extends the inner end of a 70 member 18, which is adjustably secured by means of a set screw 19. The member 18 has a downwardly extending portion terminating at its outer end in an enlarged portion 20 having a smooth rounded surface, 75 and tapering to a relatively thin lower end 21.

In the application of our invention, the device is secured around the stationary bearing 7 of the cutting disk 6 by means of the 80 screw 12, at a point adjacent said disk, and the member 18 adjusted so that the enlarged portion 20 lies immediately beyond the point where the cut takes place.

As the leather stock "A" is moved forward 85 by the feed roll 1, the skiving "B" is deflected upwardly by the tapered enlarged portion 20 of the member 18 until it strikes the wing 15, whereby it is further deflected away from the moving parts of the machine to a suitable waste receptacle, thereby precluding any 90 possibility of its winding around the shaft of the cutter disk or otherwise interfering with the efficient and economical operation of the machine. 95

While we have described our invention in the best embodiment of which we are at present aware, we do not wish to limit ourselves to the specific form disclosed herein.

Having thus described our invention, what 100 we claim is:

1. An attachment for leather skiving machines having a rotary cutting disc, comprising a member adapted to be detachably secured around the fixed bearing of the rotary 105 cutting disc, and a downwardly extending deflecting portion having an enlarged outer end adjustably carried by said member, said outer end having a smooth rounded surface and tapering downwardly, substantially as 110 described.

2. An attachment for leather skiving ma-

chines, comprising a ring shaped clamping member, and having an integral tangentially disposed wing portion, and a downwardly extending skiving deflecting portion having an 5 enlarged outer end adjustably secured to said member.

3. An attachment for leather skiving machines comprising a divided ring shaped clamping member having an integral tangentially disposed wing, and a skiving deflector carried by said clamping member, said deflector having a deflecting head located in advance of said wing portion in substantially the same vertical plane therewith 15 and in a lower horizontal plane.

4. An attachment for leather skiving machines having a cutting disc rotatably supported by a fixed bearing comprising a member adapted to be detachably secured around 20 the fixed bearing of the cutting disc and having an integral projecting lug or portion provided with an aperture, and a skiving

deflector having a shank adjustably held in said aperture, said skiving deflector being positioned adjacent the cutting portion of 25 the disc.

5. An attachment for leather skiving machines having a cutting disc rotatably supported by a fixed bearing comprising a member adapted to be detachably secured around 30 the fixed bearing of the cutting disc and having an integral projecting lug or portion provided with an aperture, and a skiving deflector having a shank adjustably held in said aperture, said skiving deflector being 35 positioned adjacent the cutting portion of the disc, said member having a rearwardly extending deflector against which the skiving is deflected by said first named deflector.

In testimony whereof, we affix our signatures. 40

NELLIE I. FOSTER.
HENRY B. LUPIEN.
